UNITED STATES PATENT OFFICE.

JOHN E. TROSTLE, OF SPRINGFIELD, MASSACHUSETTS, ASSIGNOR TO WESTINGHOUSE ELECTRIC & MANUFACTURING COMPANY, A CORPORATION OF PENNSYLVANIA.

STARTING MECHANISM FOR AUTOMOBILES.

Application filed December 16, 1920. Serial No. 431,080.

To all whom it may concern:

Be it known that I, JOHN E. TROSTLE, a citizen of the United States, and a resident of Springfield, in the county of Hampden and State of Massachusetts, have invented a new and useful Improvement in Starting Mechanisms for Automobiles, of which the following is a specification.

My invention relates to starting mechanisms for automobiles and, particularly, to starting mechanisms having motor pinions that are moved axially into mesh with engine gear wheels.

One object of my invention is to provide a starting mechanism having an electromagnet that shall move an associated armature a relatively small distance for effecting a relatively large axial movement of the motor pinion.

In a starting mechanism having a motor pinion movable axially into mesh with an engine gear wheel, an electromagnet, connected in circuit with the starting motor, has heretofore been provided for directly moving the motor pinion into mesh with the engine gear wheel. However, in such mechanism, the air gap between the frame of the magnet and the armature must be made as large as the distance through which the motor pinion is moved. Consequently, considerable power is taken by the electromagnet for shifting the motor pinion and, in many cases, to such extent as to interfere with the operation of the motor.

In a starting mechanism constructed in accordance with my invention, a magnet is connected in circuit with the starting motor. The electromagnet operates an armature which is so connected to the motor pinion that a relatively small movement of the armature effects a relatively large movement of the motor pinion. Moreover, the field-magnet winding of the motor is shunted by relatively large resistors in order to prevent complete excitation of the motor until the motor pinion is in mesh with the engine gear wheel.

Preferably, the armature of the electromagnet is connected to the motor pinion by means of two levers which are so fulcrumed as to permit a relatively small air gap between the frame of the magnet and the associated armature.

In the accompanying drawing,

Figure 1 is a sectional view of a starting mechanism constructed in accordance with my invention; and

Fig. 2 is a diagrammatic view of the electric circuits connected to the starting motor.

Referring to the drawing, a starting motor 1 is connected to an engine gear wheel 2 by means of a starting mechanism 3. The motor 1 comprises a frame 4 having an end bracket 6 and an armature 5. The end bracket 6 of the motor is preferably formed integral with a housing 7 for the starting device 3.

The shaft 8 of the motor 1 extends through the end bracket 6 and carries a motor pinion 9, which is adapted to mesh with the teeth on the engine gear wheel 2. The shaft 8 is provided with a bearing on a cylindrical projection or sleeve member 10, which extends from the end bracket 6.

The starting mechanism comprises a coil 11 which is located within the housing 7 and surrounds the sleeve member 10 on the end bracket 6. The coil 11 is preferably protected by any suitable insulating material 12. One end of the coil 11 is connected to a terminal 13 which extends through the housing 7, and the other end of the coil 11 is connected to a terminal 14 which extends through the end bracket 6.

The magnetic circuit of the electromagnet, which includes the coil 11, comprises an annular ring 15, which is fastened, in any suitable manner, to the housing 7 adjacent to the coil 11. An armature 16 is mounted on the sleeve member 10 adjacent to the annular ring 15 and is moved towards this ring upon energization of the coil 11. Adjacent to the armature 16, and mounted upon the sleeve member 10, is a collar 17, which has two oppositely-extending arms with bifurcated end portions 18 and 19. Two levers 20 and 21 are pivotally mounted in the bifurcated end portions 18 and 19 of the arm 17 and are connected to the armature 16 by means of links 22 and 23. The opposite ends of the levers 20 and 21 engage a washer 24 which is connected, in any suitable manner, to the motor pinion 9.

The motor pinion and the washer 24 are held in engagement with the two levers 20 and 21 by means of a spring member 25 which is mounted on the shaft 8 between the pinion 9 and a collar member 26. The

collar member 26 is held in position against a shoulder on the shaft 8 in any suitable manner, as by means of a nut 27.

The end bracket 6 and the housing 7 may be attached to the motor frame 4 in any suitable manner, as by means of bolts 28. The end of the housing 7 adjacent to the engine gear wheel 2 may be covered in any suitable manner, (not shown). Preferably, 10 a copper member 30 is placed between the armature 16 and the projection 10, and also between the armature 16 and the annular ring 15. Such copper member prevents sticking of the armature either to the projecting portion 10 or to the annular ring 15.

Referring to Fig. 2 of the drawing, the coil 11 is shown connected in circuit with the armature 5 and the field-magnet winding 31 of the motor 1. The coil 11 and the 20 windings of the motor 1 are adapted to be connected in circuit with any suitable battery 32 by means of a starting switch 33. Preferably, the field-magnet winding 31 is shunted by resistors 34 of relatively high 25 value in order to prevent complete excitation of the motor until the motor pinion is in mesh with the engine gear wheel. Such resistors limit the speed of the motor during the meshing operation.

30 If it is desired to rotate the engine gear wheel 2 by the starting motor 1, for starting purposes, the starting switch 33 is closed for energizing the coil 11 and for effecting limited rotation of the motor 1. Upon energization of the coil 11, the armature 16 is moved towards the annular ring 15. Such movement of the armature 16 so operates the levers 20 and 21 as to force the motor pinion 9 into engagement with the engine gear 40 wheel 2. In this regard, it should be noted that the levers 20 and 21 are so fulcrumed on the arm 17 as to effect a relatively large axial movement of the pinion 9 for a relatively small movement of the armature 16.

45 The resistors 34, as heretofore set forth, prevent the building up of the motor excitation until the meshing between the pinion 9 and the engine gear wheel 2 has been effected. When the switch 33 is opened for stopping 50 the motor 1 and for de-energizing the coil 11, the spring member 25 moves the pinion 9 out of mesh with the engine gear wheel 2.

In the starting mechanism above described, 55 it will be noted that an electromagnet is connected in circuit with the starting motor for moving the motor pinion into mesh with the engine gear wheel as soon as the circuit of the motor is closed. The air gap between the frame of the electromagnet and the associated armature is relatively small in order that such magnet shall not interfere with the operation of the starting motor. It is possible to operate the starting mechanism 60 by such limited air gap by reason of the disposition of the levers which connect the

armature of the electromagnet to the motor pinion 9.

Modifications in the mechanism and in the arrangement and location of parts may be made within the spirit and scope of my 70 invention, and such modifications are intended to be covered by the appended claims.

I claim as my invention:—

1. The combination with a shaft and a member longitudinally movable thereon, of an electromagnet on said shaft in axial alinement therewith, said electromagnet comprising an armature member, and means operable upon movement of said armature member in one direction to actuate the movable member in the opposite direction. 75

2. The combination with a shaft and a member longitudinally movable thereon, of an electromagnet having a coil surrounding said shaft in axial alinement therewith, said electromagnet comprising an armature member, and means operable upon movement of said armature member in one direction to actuate the movable member through 80 a greater distance in the opposite direction. 90

3. The combination with a shaft, and a pinion longitudinally movable thereon, of an electromagnet on said shaft and in axial alinement with said shaft and said pinion, said electromagnet having an armature member, and means for operatively connecting said pinion to said armature member for unequal movements longitudinally of 95 said shaft.

4. The combination with a motor having a shaft, and a pinion longitudinally movable thereon, of an electromagnet on said shaft in axial alinement with said shaft and said pinion, said electromagnet having an armature member, and means for operatively connecting said pinion to said armature member for unequal movements in opposite directions longitudinally of 100 said shaft. 105

5. The combination with a motor having a shaft, and a pinion longitudinally movable thereon, of an electromagnet on said shaft between the motor and the pinion and in axial alinement with said shaft and said pinion, said electromagnet having an armature member, and means comprising a pivoted lever for operatively connecting said armature member to said pinion. 110

6. The combination with a shaft, and a pinion longitudinally movable thereon, of an electromagnet on said shaft in axial alinement with said shaft and said pinion, said electromagnet having an armature member, and means comprising a pivoted lever having arms of unequal length for operatively connecting said armature member to said pinion. 115

7. The combination with a motor having a shaft, and a pinion longitudinally movable thereon, of an electromagnet on said 120 125 130

shaft between said motor and said pinion and in axial alinement with said shaft and said pinion, said electromagnet having an armature member, and means for operatively connecting said pinion to said armature member, said means comprising a stationary member and a lever pivotally supported thereby.

8. In a starting mechanism, the combination with a motor having a shaft, a pinion operated by said motor, and an engine gear wheel, of an electromagnet on said shaft in axial alinement with said pinion and said motor that is energized in series with said motor, means comprising two levers operated by said electromagnet for meshing said pinion with the engine gear wheel upon starting of the motor.

9. In a starting mechanism, the combination with a motor having a shaft, a pinion operated by said motor, and an engine gear wheel, of an electromagnet on said shaft and connected in series with said motor, said motor, said pinion and said electromagnet

being in axial alinement, means comprising 25 levers for moving the pinion into mesh with the engine gear wheel upon energization of said magnet, and resistors connected in shunt to the motor-field-magnet winding to prevent rapid rotation of the motor until 30 the pinion is in mesh with the engine gear wheel.

10. In a starting mechanism, the combination with a motor, a pinion rotatable with, and shiftably mounted on, the shaft 35 of said motor, and an engine gear wheel, of a coil mounted upon the motor frame and surrounding the motor shaft, an armature for said coil surrounding the motor shaft and operated by said coil, and two pivotally 40 mounted levers operated by said armature for moving said pinion into mesh with the engine gear wheel.

In testimony whereof, I have hereunto subscribed my name this 24th day of Nov. 45 1920.

JOHN E. TROSTLE.
